UNITED STATES PATENT OFFICE.

LESSAGE RAYMOND, OF WOODHAVEN, NEW YORK, ASSIGNOR TO CAMLIN CORSET CO. INC., A CORPORATION OF NEW YORK.

UNDERGARMENT.

Application filed March 5, 1925. Serial No. 13,020.

To all whom it may concern:

Be it known that I, LESSAGE RAYMOND, a citizen of the United States, and resident of Woodhaven, in the county of Queens and State of New York, have invented certain new and useful Improvements in Undergarments, of which the following is a specification.

This invention relates to combination undergarments for women. The object of the invention is to provide an undergarment comprising in combination a brassière and a corset so arranged that both may be worn together as practically one garment for the support of the body from below the hips and to the bust, and in which case there is a cooperative function between the brassière and the corset. Or, if desired, either of these garments may be worn separately, or another garment of similar character may be substituted for one of the combination garments.

Other objects of the invention are to provide a combination garment of modish pleasing appearance adapted to create the modern slender straight outline of figure.

Another object of the invention is to provide a combination garment in which the brassière portion is readily detachable from the corset portion, and vice versa, for cleaning purposes for instance.

Still another object of the invention is to provide a combination garment in which the brassière portion is provided with hose supporting means for better cooperative function with the corset garment and for the support of the hose.

With the foregoing objects in view my invention is embodied in a combination undergarment constructed, arranged and designed as hereinafter set forth, while reference is had to the accompanying drawing in which

Figure 1 is a front view of the garment.

Figure 2 is a rear view thereof.

Figure 3 is a front view showing the brassière portion open and detached from the corset portion.

The combination garment according to the invention consists of an upper and a lower portion formed respectively as a brassière and a corset.

The brassière portion comprises a front member 4, a right side member 5, a back 6 and a left side member 7. These several members are shaped to form a brassière by

sewing them together, either along the lines indicated in the drawing or otherwise in accordance with custom or good practise in the industry. Suitable shoulder straps as 8, 8 are provided as usual.

The lower edges of the side members 5 and 7 are provided with or formed of elastic bands 9, 9 of an elastic fabric having a stretch greatest in the horizontal direction so as to fit snug in the waist.

The front 4 is provided with a depending flap portion 10 preferably reinforced by a front strengthening piece 11. The brassière portion is openable along the one edge 12 on the line where the one side joins the front, preferably the left side as shown. In order to close the brassière at this point, there is provided suitable closing means such as hooks 13 and coacting eyes 14.

The back 6 of the brassière portion is provided with a depending flap 15 to which is attached hose supporters 16, 16 by means of long elastic bands or straps 17, 17 to bring the hose supporters at the proper height.

The hose supporters and shoulder straps are broken away and removed in Figure 3.

The corset portion is of the closed one piece step-in type, open at the top 18 and bottom 19 and comprises front and rear members 20 and 21 of fabric usually used for corsets. These members are joined by side members 22, 22 of elastic fabric.

The corset front 20 is provided with a row of hooks 23 adapted to be hooked into a row of eyes 24 on the brassière front 4. In addition the corset front has a single eye 25 adapted to be hooked into the single hook 26 at the lowest point of the brassière flap 10.

The corset back 21 carries two loops 27, 27 through which pass the hose supporting straps 17, 17. Other usual hose supporters 28 may be provided. In the drawing the shaded portion indicates elastic fabric, the unshaded portion indicates non-elastic fabric.

The garment is put on by stepping into the corset portion and placing it in proper position around the hips. Thereafter the brassière portion is slipped on like a vest with the shoulder straps over the shoulders of the wearer. The hose supporters 16-17 are passed through the loops 27 and the brassière is closed around the body and combined with the corset by hooking the

eyes 24 over the hooks 23 (which point downwardly) and hooking the eye 26 over the hook 25. Thereafter the hooks 13 are hooked into the eyes 14.

5 As thus put on and worn it will be noted that the two parts of the combination garment are properly attached to each other at the front and that the hook and eye connection 25—26 prevents the brassière from creeping up and becoming displaced.

10 The brassière fits easily and comfortably around the body because the lower edges of the brassière overlap the upper edge of the corset. The elastic bands 9 serve to confine 15 the brassière to the body at the upper edge of the corset and prevents bunching.

15 The back of the brassière is likewise held down by the hose supporters 16—17 when hooked into the hose. In sitting down or bending the flap 15 prevents the corset edge 20 of being turned over to annoy the wearer, and the straps 17, 17 serve to keep the brassière properly in position in the back. The loops 27, 27 serve to confine the straps 25 17 to the body and separates said straps to prevent twisting or bunching.

The supporters 17 and 28 serve to support the hose.

30 The garment is very simple in construction. It lies close to the body to confine and produce the proper outline. Either part of the garment may be worn separately as is obvious.

While I have disclosed my invention in its

preferred form, nevertheless I do not wish 35 to be limited strictly to the form illustrated. Thus I contemplate within the principle and objects of the invention that modifications may be found convenient and desirable. Thus for instance in place of hooks and eyes 40 other fastening means may be used. Or the brassière may be permanently attached to the corset along the lines of members 24—23 by sewing, yet by ripping the short seam required, the garment portions may be separated. In the case of sewing the two parts together I may or may not use the front flap 10.

I claim:—

As a new article of manufacture, an undergarment of the character described comprising a brassière garment the front of 50 which is adapted to be opened and closed to put the garment off and on, fastening means for said front, a step-in corset garment, 55 means for securing the said front of the brassière garment to the corset garment at the front of the latter, hose supporters secured to the corset garment at the lower front edge thereof, other hose supporters, 60 elastic straps for securing the latter to the back of the said brassière garment and a piece of fabric secured to the back of the corset garment and forming loops through 65 which the said elastic straps pass as and for the purpose set forth.

LESSAGE RAYMOND.
